CLAIM

The ornamental design for a game glove, as shown and described.

DESCRIPTION

FIG. 1 is a bottom, front, right side perspective view of a right hand game glove showing the first embodiment of my design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a bottom plan view thereof;

FIG. 7 is a top plan view thereof;

FIG. 8 is a bottom, front, left side perspective view of a left hand game glove showing the second embodiment of my design

FIG. 9 as a rear elevation view thereof;

FIG. 10 is a front elevation view thereof;

FIG. 11 is a left side elevation view thereof;

FIG. 12 is a right side elevation view thereof;

FIG. 13 is a bottom plan view thereof; and,

FIG. 14 is a top plan view thereof.

The broken lines showing of the wrist portion of the glove are for illustrative purposes only and form no part of the claimed design.
